By his Attorney,

J. R. Littell

UNITED STATES PATENT OFFICE.

LAWRENCE HENRY TAYLOR, OF MUSCATINE, IOWA.

SLEEVE AND CUFF HOLDER.

SPECIFICATION forming part of Letters Patent No. 475,905, dated May 31, 1892.

Application filed July 13, 1891. Serial No. 399,389. (No model.)

To all whom it may concern:

Be it known that I, LAWRENCE HENRY TAYLOR, a citizen of the United States, residing at Muscatine, in the county of Muscatine and 5 State of Iowa, have invented certain new and useful Improvements in Sleeve and Cuff Holders; and I do hereby declare that the following is a full, clear, and exact description of the invention, which will enable others skilled 10 in the art to which it appertains to make and use the same.

This invention relates to a combined sleeve and cuff holder; and it has for its object to provide a device of this character designed to 15 support the cuff in the desired location upon the arm and at the same time retain the wristband of the shirt in its proper position with relation to the cuff.

A further object of the invention is to provide 20 a simple and improved article of this character designed to be entirely constructed in a single piece and which will, furthermore, possess advantages in point of inexpensiveness, durability, ease of adjustment, and general 25 efficiency.

In the drawings, in which similar letters of 30 reference denote corresponding parts, Figure 1 is a perspective view illustrating the application of my invention. Fig. 2 is a longitudinal sectional view illustrating the same. Fig. 3 is a detail perspective view of the device detached and showing the same as constructed of wire or strip metal. Fig. 4 is a 35 similar view of the device as manufactured from sheet metal.

Referring to the drawings, A designates the combined sleeve and cuff holder, which is preferably formed of a single piece of wire or sheet metal. At the rear end of the device is 40 an arm B, having provided therein a V-shaped slot b, adapted to receive a portion of the shirt-sleeve, thus securing the holder thereto. A forwardly-extending arm C is provided at the outer end of the holder, which has a slot c. 45 The latter is adapted to receive the shank s of the sleeve - button S, and, being of less breadth than the diameter of the head s' of said button, accidental disengagement of the button, therefore, is obviated.

50 Between the arms B and C and connecting the same is an enlarged portion D, having an approximately-circular opening d. The lat-

ter serves the twofold purpose of admitting the head of the sleeve-button to permit the shank of the latter to be received by the slot 55 c and to receive the portion of the shirt-sleeve to be wedged in the slot b.

E designates the cuff-securer, which is located at the outer end of the arm C. The securer E consists of an arm bent upwardly at 60 approximately right angles to said arm C, as shown at e, and thence bent forwardly and downwardly for about one-half the length of the portion e, as at e', the arm terminating in a forward extension e², parallel with the plane 65 of the arm C and adapted to bear upon the outer surface of the cuff to prevent disengagement with the latter.

The operation and advantages of my invention will be readily understood by those skilled 70 in the art to which it appertains.

In manufacture it will be obvious that the device can be made either of a single piece of wire or strip of metal or it may be stamped from sheet metal, in any of which cases the 75 entire device is formed in a single piece. When constructed of wire or strip metal, one end is bent to form the cuff-securer, the wire or strip being then bent to form the other parts, and, lastly, the free end is bent and secured around the portion e of the cuff-securer, as shown in Fig. 3. When formed of sheet metal, the entire device is struck therefrom by a suitable die, the cuff-securer being struck up at the outer end of the device and into the 85 shape specified. (See Fig. 4.)

In practice the cuff-securer is first passed through the lower buttonholes of the cuff, and the latter then drawn over the hand. When the opening d coincides with the sleeve- 90 button, the head of the latter is projected through the opening, so that the slot c will receive the button-shank. After the cuff has been adjusted, as desired, a portion of the shirt-sleeve is forced by the finger through 95 the opening d and then drawn into the slot e, securely fastening the device to the sleeve.

My invention serves the twofold purpose of retaining the cuff and shirt-sleeve in adjusted position, the wristband being thus held in its 100 proper relation to the cuff. By this construction the wristband is prevented from working below the cuff, as frequently occurs in devices of this character.

I claim as my invention—

As an improved article of manufacture, a combined sleeve and cuff holder comprising a rearwardly-projecting arm B, provided with 5 a V-shaped slot b, adapted to receive a portion of the sleeve, a forwardly-extending arm C, provided with a slot c of approximately the same breadth throughout its length and adapted to receive the sleeve-button shank 10 and retain said button, whereby the wristband is held in its proper relation to the cuff, an enlarged portion D, connecting said arms and having an opening d, and a cuff-securer E, located at the outer end of the arm C and

consisting of an outturned portion e, a downwardly and forwardly extending portion e', and an extension e², approximately parallel with the plane of the arm C, said securer being adapted to retain the cuff against disengagement therefrom in either direction, substantially as and for the purpose set forth. 15 20

In testimony whereof I affix my signature in presence of two witnesses.

LAWRENCE HENRY TAYLOR.
